H. G. WRIGHT.

CHAIR.

APPLICATION FILED DEC. 22, 1921.

1,432,144.

Patented Oct. 17, 1922.

UNITED STATES PATENT OFFICE.

HOWARD G. WRIGHT, OF BON AIR, VIRGINIA.

CHAIR.

Application filed December 22, 1921. Serial No. 524,224.

To all whom it may concern:

Be it known that I, HOWARD G. WRIGHT, a citizen of the United States, residing at Bon Air, in the county of Chesterfield and 5 State of Virginia, have invented certain new and useful Improvements in Chairs, of which the following is a specification.

This invention relates to certain new and useful improvements in chairs and it more 10 particularly relates to the class of chairs provided with backs, such as are used in theaters and other public places of amusement.

One of the objects of my invention is to provide the seat to such chairs as above set forth with means to raise the seat consisting 15 of a spiral spring, one end of which surrounds and is attached to a bracket extending from the side standard of the chair at a point below the seat. The other end 20 of the spring is elongated and presses against the bottom of the seat so that when such seat is unoccupied, the pressure of the spring automatically causes it to turn through an arc of about 45 degrees and to 25 rest in a position substantially parallel to and against the back of the chair.

Another object of my invention is to so construct the device as to bring about economy of material used in each device and economy of labor required to attach the 30 devices to a row of chairs, the construction being such as to operate a seat to the left as well as to the right of the side standard to which it is attached, so that instead of applying a device to each side standard of a 35 chair, it is necessary to apply one only to each alternate side standard; in other words, to but one half the number of chairs in place.

With these and other objects in view 40 which may be incident to my improvements, the invention consists in the parts and combinations to be hereinafter set forth and claimed, with the understanding that the several necessary elements comprising my 45 invention, may be varied in construction, proportions and arrangement, without departing from the spirit and scope of the appended claims.

In order to make my invention more 50 clearly understood, I have shown in the accompanying drawings means for carrying the same into practical effect, without limiting the improvements in their useful applications to the particular constructions, which

for the purpose of explanation, have been 55 made the subject of illustration.

In the drawings:

Figure 1 is a side elevation of the chair showing the seat lowered.

Figure 2 is a similar view showing the 60 seat raised.

Figure 3 is a sectional view along the line 3—3 of Figure 2, showing my improved device attached to the side standards of a 65 chair.

Figure 4 is a sectional view on the line 4—4 of Figure 3, showing the front and rear standards of the chair and the bracket to which the spring seat lifting arms is attached.

Figure 5 is a detail view showing the lower end of the bracket attached to the side standard of the chair in a modified manner.

The numeral 1 refers to the side frames or standards of a chair the same being provided with feet 2 cast integrally therewith and provided with apertures through which are inserted bolts or screws 3 by means of which the chair is firmly secured to the floor. Said standards are connected together in the rear by a back attached to each side member, and by a side brace 4 riveted or otherwise secured to the front and rear side standards by bolts 5. The numeral 6 represents a yoke formed of a single piece 75 of metal which is bent in the form more clearly shown in Figure 4 so as to readily embrace both the front and rear standards to which it is securely bound by means of a bolt 7. A set-screw or bolt 8 is provided 80 at the bend 8' of the yoke 6 whereby it can be more closely and readily adjusted and held in place. When the chairs are located upon a gently rising floor, as is usually the case in that part of an auditorium design- 85

nated the orchestra chairs, this set-screw is placed so as to be operated against the rear standard. When, however, the chairs are otherwise placed, such for instance, as in the gallery of a theatre, it would be impractical to operate said set-screw or bolt 95 from the rear position and in that case the yoke is reversed so that the set-screw is operated against the front standard instead of the rear standard.

Each member 4 is provided on each side at or near its center with an outstanding bent portion or boss 9 which is apertured

for the reception of a screw or bolt 10, the purpose of which is to pivotally support a suitable arm 11 the upper member 12 of which is provided with apertured flanges 5 13 to which the seat is secured by screws or otherwise.

Below the boss 9 are brackets 14. The lower portion of each bracket is turned upon itself in such a manner as to embrace 10 one of the side members 15 of the yoke 6 to which it is secured by bolts 16. Just above (the point of) the bolt and at a point 17 the bracket is turned at an angle of about 45 degrees for a short distance and at 18 is 15 again turned at a reverse angle so as to form a straight member 19 which extends parallel to the side standard, and to said member 19 there is attached a screw-threaded bar or bolt 20 around which is coiled a 20 spiral spring 21. One end 22 of said spring abuts against the straight member 19 and the other end is elongated in a straight line to form the member 23, the greater portion of which contacts with the bottom of the 25 seat 24. At the end of the spiral spring opposite the member 19 the bolt 20 is provided with a washer 25 which abuts against the head of the bolt and tends to hold the spring in its proper place.

30 The modification shown in Figure 5 is intended to show another manner of securing the brackets to the side standard. The figure shows an absence of the fastening bolts 16 and it is the intention sometimes to secure the brackets to the side standard by spot-welding rather than by bolts.

It will be observed while the operation of each seat is distinct and separate from the operation of the adjacent seat, there is decided economy in being able to so manufacture the device that it will serve two chairs, and a further economy lies in the reduced 40

amount of labor required in placing it in position upon each alternate chair instead of every chair.

Upon inspection of the drawings it will be obvious that with my improved form of seat there is nothing to prevent a hat support from being placed thereunder, and that the chair may be manufactured and sold 45 with or without such support, in accordance with the wishes and order of the customer. 50

While I have shown and described the preferred embodiment of my invention, I 55 wish it to be understood that I do not confine myself to the precise details of construction herein set forth, by way of illustration, as it is apparent that many changes and variations may be made therein, by those skilled in the art, without departing 60 from the spirit of the invention, or exceeding the scope of the appended claims.

I claim:

1. A device of the character described comprising a yoke adapted to be applied to the side standards of a chair below the seat pivot, brackets extending outwardly and upwardly from opposite sides of the yoke and into the seat axis, a spring mounted on each bracket to contact with a seat to the right and to the left respectively of the yoke, to automatically tilt said respective seats when unoccupied.

2. A device of the character described comprising a split ring yoke to embrace the side standards of a chair, means to solidly lock said yoke to the side standards, an up-standing bracket on said yoke, and a spring, one end of said spring contacting with the seat on the standards to automatically tilt 65 70 75 the seat when unoccupied, the other end of the spring secured to the said bracket.

In testimony whereof I affix my signature.
HOWARD G. WRIGHT.
